PRECIPITATION METHOD FOR THE SEPARATION OF PLUTONIUM AND RARE EARTHS

Stanley G. Thompson, Richmond, Calif., assignor to the United States of America as represented by the United States Atomic Energy Commission

No Drawing. Application November 17, 1948
Serial No. 69,617

2 Claims. (Cl. 23—14.5)

This invention relates to the separation and purification of plutonium and particularly to the separation of plutonium from radioactive elements of lower atomic weight. This invention is also concerned with a new and useful composition of plutonium.

In this specification and claims, the name of the element designates generically the element both in its free state and combined in a compound. The element in its free state is designated by the term "elemental" or by its specific state, such as "metallic."

An object of the present invention is to provide a method for separating plutonium from certain elements with which it is contaminated as a result of its formation by the neutron irradiation of uranium and particularly the separation from the rare earths with which it is contaminated.

A further object of the present invention is to provide a novel and useful composition of plutonium.

Additional objects and advantages of this invention will be evident from the following description.

In accordance with the present invention, it has been found that plutonium ions in the tetravalent state may be separated from an aqueous solution by precipitating the tetravalent plutonium ions with pyrophosphate anions. It has further been found that tetravalent plutonium ions contained in an aqueous solution in a concentration so low that said plutonium ions will not be precipitated directly as the pyrophosphate may be removed substantially quantitatively from the solution with a carrier precipitate of a heavy metal pyrophosphate which is insoluble in an aqueous acidic solution. The pyrophosphates which have been found to be most useful as plutonium carriers include uranous-, ceric-, zirconium-, and particularly thorium pyrophosphate. These carrier pyrophosphates, for example thorium pyrophosphate, have been found to carry tetravalent plutonium ion quantitatively, but these pyrophosphates do not carry the trivalent or hexavalent plutonium ion, the trivalent rare earth ions or the uranyl ion.

These discoveries form the basis of a process for separating plutonium from contaminants which is a fundamental part of this invention. Broadly, this process comprises forming an aqueous acidic solution of plutonium ions in the tetravalent state and elements with which it is normally contaminated in neutron irradiated uranium, treating this solution with a soluble thorium compound and a soluble pyrophosphate compound whereby a carrier precipitate of thorium pyrophosphate is formed in said solution, separating the thorium pyrophosphate precipitate, together with the tetravalent plutonium carried with said precipitate, dissolving said precipitate, oxidizing the tetravalent plutonium ions contained in the new solution to the hexavalent state, and re-precipitating the thorium pyrophosphate, leaving the hexavalent plutonium ions in the solution in a substantially pure state.

This process is not only useful in obtaining plutonium in an uncontaminated state, but is also useful in obtaining radioactive fission products. The usefulness of these

2

radioactive fission products as tracers and therapeutic agents is well known.

The plutonium may be placed in solution by dissolving a neutron irradiated uranium mass in an aqueous solution of a strong inorganic acid or a highly ionized organic acid, which does not form complexes with heavy metal ions. In general, nitric acid and hydrochloric acid are to be preferred, although sulfuric acid may be used if consideration is given to the tendency of sulfuric acid to form plutonium complexes. It will also be apparent that certain acids are excluded depending upon the choice of cation for the carrier precipitate. Thus, if thorium pyrophosphate were to be used as a carrier, an acid would not be chosen which would form an insoluble compound with thorium. Other considerations, such as the formation of complex ions, may exclude other acids in certain instances. However, nitric acid and hydrochloric acid are highly satisfactory in all cases and it is unnecessary to attempt to use other acids for the adjustment of the pH of the solution. After the plutonium is brought into the solution the H^+ ion concentration of the solution should be adjusted so that the solution is acid. It is essential that the solution be acid prior to the precipitation step if the plutonium is to be separated from trivalent rare earth contaminants by the precipitation step since the trivalent rare earth pyrophosphates may precipitate in other than an acid solution. The upper limit of the acid concentration in the solution, however, is not critical since the carrier and tetravalent plutonium pyrophosphates are not soluble even in concentrated acids. For example, it has been found that a mixture of thorium and plutonium pyrophosphate will not dissolve in 16 N nitric acid to any appreciable extent. An acidity of between 0.5 and 2 N has been found to give satisfactory results.

It is important that the plutonium be present in the solution in the tetravalent state since it has been found that only the tetravalent plutonium ions form an insoluble pyrophosphate in acid solutions. Relatively stable states of plutonium in the ionic state in aqueous solution are the +3, +4 and the +6 states. The normal state of plutonium when it is placed in solution by the dissolving of neutron irradiated uranium in nitric acid or hydrochloric acid is the +4 state, so that if the solution is formed in this manner, ordinarily, no further precautions need be taken to insure that the plutonium is in solution in the tetravalent state. However, should the plutonium be placed in solution by any other method which would make the valence state of the plutonium ions questionable, the plutonium may be treated with suitable oxidizing or reducing agents, as the case may be, to insure that it is in the tetravalent state. The oxidation-reduction potentials (referred to the normal hydrogen electrode) linking Pu^{+3} , Pu^{+4} , and Pu^{+6} in 1 M nitric acid at 30° C. are:

55.	Pu^{+3}	—0.92 volt	Pu^{+4}	—1.11 volt	Pu^{+6}
60.				1.04 volts	

By referring to a table of oxidation and reduction agents with their respective potentials, such as given by Latimer and Hildebrand in the *Handbook of Chemistry and Physics*, suitable agents may be chosen to treat the plutonium contained in solution to insure that it is present in the tetravalent state.

The removal of the tetravalent plutonium from the solution with a carrier may be effected by the precipitation of the carrier in the solution, by the treatment of the solution containing plutonium with the preformed carrier, or by passing the solution through a bed of the carrier. However, it has been found preferable to form the carrier in the solution. This may be done by introducing a soluble compound containing the cation, for

example thorium chloride or thorium nitrate where thorium pyrophosphate is to be the carrier, into the solution. The carrier precipitate may then be formed by introducing a soluble pyrophosphate compound, such as potassium or sodium pyrophosphate or pyrophosphoric acid into the solution. The order or method of contacting the plutonium-containing solution with the carrier is not essential and variations may be introduced without departing from the method of the invention. The pyrophosphate carriers herein described are soluble in an excess of pyrophosphate, presumably by the formation of pyrophosphate complexes, such as thorium pyrophosphate complex. Although a precipitate of thorium pyrophosphate can be formed where the molarity of the pyrophosphate in solution is ten times as great as the molarity of the thorium, it is desirable to form the carrier pyrophosphate in a solution where the molarities of the cation and of the pyrophosphate do not differ too greatly from stoichiometric proportions. It has also been found desirable to carry out the carrier precipitation at room temperature because of the tendency of tetravalent plutonium ions to oxidize in warm nitric acid, and the precipitation is usually complete with relatively short periods of digestion even at room temperature. The thorium pyrophosphate-plutonium pyrophosphate precipitate is a white crystalline precipitate and it may be separated from the solution by filtration, decantation, or preferably centrifugation.

This step of precipitating tetravalent plutonium with a pyrophosphate carrier may be used to separate plutonium from most elements with which it is contaminated, except those which are normally tetravalent in aqueous acidic solution. Thus, this step will separate plutonium from the rare earths (including cerium, which will normally be present in aqueous solution in the trivalent state), Rb, Sr, Y, Cs, Ba, Kr, and Xe. The carrier precipitation step described above may also be used to separate plutonium from uranium because by the normal process of dissolving neutron irradiated uranium in nitric acid, the uranium is present in the uranyl nitrate hexahydrate thus formed in the hexavalent state which is not carried with a pyrophosphate carrier, and the plutonium is present in the tetravalent state. This step of the process may also be used as an analytical procedure to determine the relative amounts of trivalent, tetravalent and hexavalent plutonium in solution, since the tetravalent plutonium will be carried with a pyrophosphate precipitate, while the trivalent and hexavalent plutonium will remain in solution. The composition of

also has uses independent of its uses outlined above. For example, plutonium may be conveniently transported in the form of this composition.

The foregoing step, although useful individually for the purposes outlined above, may also be employed as a step in the following procedure which is a more complete plutonium separation process. The carrier precipitate containing the plutonium pyrophosphate obtained in the preceding step may be dissolved by treatment of the precipitate with an excess of pyrophosphate ion. For example, the thorium-plutonium pyrophosphate may be introduced into a pyrophosphoric acid solution or into a solution of an alkali metal pyrophosphate wherein the pyrophosphate ion is in considerable excess with respect to the combined amount of plutonium and thorium. Following the dissolution of the carrier precipitate, the plutonium is oxidized to the hexavalent state. This may be done by treatment of the solution with a suitable oxidizing agent as determined by the oxidation potential of plutonium given above and reference to a standard oxidation-reduction table. Particularly suitable oxidizing agents have been found to be the alkali metal bismuthates, alkali metal permanganates, and alkali metal dichromates. Following the oxidation of the plutonium to the hexavalent

state, the carrier precipitate may again be precipitated by introducing a soluble compound containing the carrier cation into the solution so that the ratio of carrier cation to pyrophosphate ion approaches stoichiometric proportions. The precipitate is then separated from the solution. This step not only frees the plutonium from the carrier but is also effective in removing certain additional contaminants from the solution. Thus, those fission products, such as zirconium and tin, having a valence state of +4, but no higher valence state, which may have been carried by the original carrier precipitate, will again be carried by the carrier precipitate, since the oxidation step will not change these cations from the pyrophosphate insoluble state. Even fission products having both tetravalent and higher oxidation states may be separated from plutonium by this process by the suitable selection of an oxidizing agent in this final step so that the plutonium but not the contaminant is oxidized from the tetravalent state.

The decontamination of the plutonium may be greatly increased by carrying out the process as a cycle and repeating the cycle. Thus, following the re-precipitation of the carrier precipitate, the plutonium may be reduced to the tetravalent state, thus completing the cycle and the cycle repeated as often as required to obtain the decontamination desired.

This invention will be further illustrated by the following specific example.

Example

Four hundred fifty micrograms of $\text{Th}(\text{NO}_3)_4$ and 600 micrograms of LaCl_3 were dissolved in 1 M HCl. Tracer quantities of $\text{Pu}(\text{NO}_3)_3$ and $\text{Pu}(\text{NO}_3)_4$ were introduced into this solution. Two hundred sixty-six micrograms of $\text{Na}_4\text{P}_2\text{O}_7$ were then introduced into an aliquot of the above solution having a final volume of 0.12 ml. A white crystalline precipitate formed and this was digested at room temperature with stirring for eight minutes. This precipitate was then separated from the solution by centrifugation. The solution and the precipitate were analyzed by radiometric methods and it was found that 98.4% of the tetravalent plutonium had carried with the ThP_2O_7 . More than 99% of the trivalent plutonium and more than 99% of the lanthanum remained in the solution. The $\text{ThP}_2\text{O}_7 - \text{PuP}_2\text{O}_7$ was then dissolved in a $\text{Na}_4\text{P}_2\text{O}_7$ solution. Following the separation of the ThP_2O_7 plutonium carrier precipitate from the solution containing the lanthanum and trivalent plutonium, the precipitate is dissolved by introducing a precipitate into 0.15 ml. of 0.1 M $\text{Na}_4\text{P}_2\text{O}_7$ which is 1 M in HNO_3 . The precipitate is heated to 60° C. and maintained at that temperature for approximately one hour to facilitate dissolution. Following the dissolution of the precipitate, the tetravalent plutonium is oxidized to the hexavalent state by treatment with NaBiO_3 . The solution is then contacted with 3000 micrograms of Th^{+4} (as the nitrate), thus causing a precipitate of ThP_2O_7 to form. This precipitate was digested for ten minutes at room temperature with stirring and then separated from the solution. Analysis of precipitate discloses that less than 1% of the plutonium carries with the precipitate.

It is to be understood, of course, that the above example is merely illustrative and does not limit the scope of this invention. Other mixtures of plutonium with elements of lower atomic numbers may be employed as starting materials and other acids and other cations may be substituted for those of the above example, within the scope of the foregoing description. Likewise, the process of the example may be modified by incorporating other purification steps in addition to the use of the steps previously described. In general, it may be said that the use of any equivalents or modifications of procedure which would naturally occur to one skilled in the art is included in the scope of this invention. Only such limitations should be imposed on the scope of this invention as are indicated in the appended claims.

What is claimed is:

1. A method of purifying plutonium, which comprises introducing into an aqueous acidic solution of tetravalent plutonium a soluble thorium compound and a soluble pyrophosphate compound, separating the

precipitate thus formed from the solution, dissolving said precipitate, adding to the solution thus formed an oxidizing agent having a potential more negative than -1.11 volts, whereby the tetravalent plutonium is converted to the hexavalent state, precipitating thorium pyrophosphate in the resulting solution, and separating said thorium pyrophosphate from the solution of oxidized plutonium.

2. A method of separating plutonium from elements with which it is normally contaminated in neutron irradiated uranium, which comprises forming an aqueous acidic solution containing said plutonium in the tetravalent state and contaminants, introducing into said solu-

tion a soluble thorium compound and a soluble pyrophosphate compound in approximately stoichiometric proportions, separating the $\text{ThP}_2\text{O}_7 - \text{PuP}_2\text{O}_7$ precipitate thus formed from the solution, dissolving said precipitate, adding to the solution thus formed an oxidizing agent having a potential more negative than -1.11 volts, whereby the plutonium is converted to the hexavalent state, precipitating the thorium pyrophosphate and separating said thorium pyrophosphate precipitate from the solution containing the hexavalent plutonium.
